FLOAT VALVE GUIDE FOR WATER CLOSET TANK

Orvan J. Bennett, Fort Lupton, Colo., assignor to Orvan J. Bennett, Fort Lupton, Jack E. Bennett, Denver, and Aldena A. Baskor, Longmont, Colo.

Filed Aug. 27, 1965, Ser. No. 483,260
3 Claims. (Cl. 4-57)

ABSTRACT OF THE DISCLOSURE

The invention concerns a float valve guide for a standard water closet tank. The guide replaces the conventional metal sleeve through which the lift rod on the float valve would conventionally extend. The guide is formed as an inverted, cup-like structure adapted to receive the float valve. It has an enlarged orifice in its top to receive the boss at the top of the float valve.

The cup-shaped float valve guide is sized and positioned to receive and to hold the float valve a suitable distance above the entrance seat of the discharge pipe at the floor of the water tank so that it will drop upon the seat as the tank drains. When lifted, the float valve fits loosely within the guide, with the float valve boss being in the orifice top. When the float valve is dropped onto the seat to close the water tank, the lift rod is in the orifice where it is permitted to swing to any of a number of various positions which the float valve might assume while it is moving to its seat.

This invention relates to water closet tanks and more particularly to float valve guides therefor, a primary object of the invention being to provide a novel and improved guiding arrangement for the float valve of a water closet tank which effects enhanced and reliable operation without maintenance for a long period of time. As such, the invention will be referred to as a "float valve guide."

The construction of a water closet tank, its controls, the intake valve and the float valve which closes the outlet have become almost completely standardized. Moreover, most parts needed to repair these tanks are easily obtained at low cost and may be installed by anyone without the need for special tools or skills. Perhaps the most vexing problem encountered in the operation of a conventional water closet tank occurs whenever the rod holding the float valve becomes worn or rusted, or when the guide holding this rod becomes worn or accidentally misaligned. This will cause the float valve to stick, not seat properly and leak, often in an erratic manner with the float valve functioning properly for awhile and then sticking for no apparent reason. Another diametrically opposite problem lies in the fact that when the float valve is properly operating in its guide, it will always seat in the same position, and this tends to wear out the valve much quicker than if it were to be seated in a slightly different position upon each operation.

Many different types of valves, such as hinged valves, have been proposed and devised to improve the performance of a conventional water closet, and while some are worthwhile improvements, none have been generally accepted. It appears that most people are so familiar with a conventional water closet construction, that they are reluctant to change the components therein, and are especially reluctant to use any construction which requires anything other than easily available float valves and the simple, cheap lift rods which are attached to the float valve and to the lift lever, and which must be replaced from time to time.

The present invention was conceived and developed with the foregoing considerations in view, and comprises, in essence, a float valve guiding structure which replaces

2

the restrictive rod guide of a conventional unit and which is distinctive in that the float valve itself is guided to its seat, and the lift rod attached to the float valve is not held or restricted in any passageways which may wear.

5 Accordingly, another object of the invention is to provide a novel and improved float valve guide for a water closet tank which is adapted to be installed in a conventional water closet tank to replace the conventional rod guide without modifying or altering the other conventional components in the tank in any way whatsoever, so that standard, easily-available float valves and rods may be used whenever maintenance is required.

Another object of the invention is to provide a novel and improved float valve guide for a water closet tank 15 which gives the float valve a moderate degree of freedom of movement, but at the same time precisely guides it to a proper seating position upon every operation, also with the seating action occurring at slightly different positions on the body of the valve upon each operation to provide 20 for a maximum operative life of the float valve.

Another object of the invention is to provide a novel and improved float valve guide for a water closet tank which does not need to be set in a precise manner for 25 proper operation and which eliminates problems concerned with faulty operation of a water closet because of wear or slight misalignment of the components therein.

Another object of the invention is to provide a novel and improved float valve guide for a water closet tank which may be used interchangeably with practically any 30 conventional unit although small differences in dimensions will occur in the various different types of water closet units.

Other objects of the invention are to provide a novel and improved float valve guide for a water closet tank 35 which is a simple, low-cost and easily-installed unit and may be manufactured from materials which will permit it to last for the life of the tank.

With the foregoing and other objects in view, all of 40 which more fully hereinafter appear, my invention comprises certain constructions, combinations and arrangements of parts and elements as hereinafter described, defined in the appended claims and illustrated in preferred embodiment in the accompanying drawing, in which:

45 FIGURE 1 is a front elevation view of a water closet tank, but with a substantial portion of the front wall of the tank being removed to show the interior thereof and with the improved float valve mounted in position above the outlet of the tank.

50 FIGURE 2 is a fragmentary sectional and plan view of the tank interior as taken from the indicated line 2-2 at FIG. 1, but on an enlarged scale.

55 FIGURE 3 is a sectional elevational view as taken from the indicated line 3-3 at FIG. 2.

FIGURE 4 is an isometric view of the float valve guide per se.

FIGURE 5 is a plan view of a float valve guide, as from the indicated arrow 5 at FIG. 4, but illustrating a modified construction of the same.

60 FIGURE 6 is a fragmentary sectional elevation view, similar to FIG. 3, but showing the float valve as being lifted for discharge of the water from the tank.

65 FIGURE 7 is a fragmentary sectional elevational view, similar to FIG. 3, but illustrating at one extreme position which the float valve may assume when it returns to the seat and with broken lines indicating another position which the float valve may assume when it returns to the seat.

Referring more particularly to the drawing, the conventional water closet tank, wherein the improved valve guide is used, will be first described. FIG. 1 is illustrative of a conventional water closet tank T, a box-like unit having

comparatively narrow sidewalls *s*, a bottom *b*, a front wall *f* and a rear wall *r*, a lid *l* to complete the unit. This tank may be mounted either upon a wall behind a water closet or upon the water closet itself in any conventional manner, not shown. An inlet line *10* extends upwardly through the bottom *b* at one side of the tank to upstand within the tank with a shut off valve *11* being affixed to the top of the line *10* near the top of the tank. This shut off valve is closed by a lever *12* having a float *13* at its outer end, the lever being adjusted to permit the tank to fill to a selected level before being shut off.

The outlet structure for the tank is at an opening *14* located at the center of the bottom *b* of the tank, and this outlet is formed as a pre-assembled structure carried upon a short, tubular discharge pipe *15* which is adapted to be mounted within the opening *14*. The pipe *15* is formed with a belled entrance *16* which functions as a valve seat. A flange *17* girdles the pipe *15* a short distance below the seat and is adapted to rest upon a washer gasket *18* which, in turn, rests upon the bottom of the tank about the opening *14*, with the pipe *15* extending downwardly and through the opening. This lower portion of the pipe is externally threaded, as at *19*, to receive a lock nut *20* which may be turned against a washer *21* at the underside of the tank bottom, this arrangement being effective to secure the outlet structure to the bottom of the tank with a water-tight fit. The bottom of this pipe *15* may be connected to a conduit or directly to the back of a closet bowl in any conventional manner, not shown.

The outlet structure also includes an overflow pipe *22* which upstands from an arm *23* which, in turn, outstands laterally from the discharge pipe *15* in the short space between the entrance *16* and the mounting flange *17*, the arm *23* including a passageway *24* opening into the side of the pipe and communicating with the overflow pipe.

A resilient, hollow float valve *25* is adapted to close the outlet by seating upon the outlet entrance *16* and is formed of rubber or a suitable rubber-like material. This float is conventionally formed with a lower portion *26* being substantially hemispherical, and constituting the seating portion thereof. An opening *27* is located at the bottom of this hemispherical seating portion to drain the valve whenever it is seated. The upper portion, above the equator of the seating hemisphere *26*, is formed as a flat-sloped shoulder *28* having a boss *29* upstanding from the center of the valve. The boss *29* includes a short, tubular insert *30* of rigid material which is internally threaded to receive a lift rod *31* which upstands from the valve to extend upwardly into the tank.

The lift rod *31* is a rigid, wire-like member approximately four inches long, having threads *32* at its base, connecting it into the insert *30*, and an eye *33* at its top which serves as an abutment for a pull rod *34*. The pull rod *34* is slidably connected to the lift rod and is adapted to extend upwardly from the lift rod to a lift arm near the top of the tank. The pull rod is offset from the lift rod by having its lower end turned laterally to form a short offset *35*. This offset terminates as a slide eye *36* through which the lift rod *31* extends. The upper end of the pull rod *34* is connected to the lift arm *37* near the top of the tank. This lift arm, in turn, is carried on a pivot, not shown, which extends through the front wall of the water tank to carry an external hand level *38*.

This conventional arrangement of components for a water closet tank is fully operative even without a valve guide, although such operation would not be dependable. The hand lever *38* may be depressed to raise the lift arm *37* which, in turn, by pulling the pull rod *34* and lift rod *31* upwardly, lifts the float valve *25* from its seat *16* to initiate a flushing action. Once the hollow float valve *25* is pulled away from the seat *16*, it rises towards the water surface within the tank with the lift rod *31* sliding upwardly in the eye *36* of the pull rod. As the tank empties, the float surface within the tank with the lift rod *31* sliding upwardly in the eye *36* of the pull rod. As the tank

empties, the float valve then drops downwardly and finally into position upon the outlet to initiate another cycle of operation.

The improved valve guide *40* is formed as an inverted, cup-like structure having a cylindrical wall *41* depending from a top *42* as a skirt. This skirt *41* is approximately one-fourth inch greater in diameter than the equator of the float valve *25* and has a height approximately the same as the height of the float valve, for in operation of the unit, the float valve will move upwardly into this guide to fit loosely therein. The top *42* is formed with an enlarged central orifice *43* through which the lift rod *31* extends, with the orifice *43* being sized to receive the boss *29* on the float valve with a moderately loose fit, as in the manner illustrated at FIG. 6.

This valve guide *40* is carried upon an arm *44* which extends across the top *40* to reinforce it and extends laterally and to one side thereof for connection with the overflow pipe *22*. This connection of the arm *44* with the overflow pipe *22* may be in various ways. The arm illustrated at FIG. 3 includes an orifice *45* extending through it which is reinforced by a depending hub *46* to hold the arm in a substantially rigid, outstanding position.

It is contemplated that this valve guide *40* may be manufactured of a comparatively stiff, but resilient material, such as a moderately hard rubber so that it will normally retain its shape when in use, but will yield to shock or undue pressure to prevent its breaking. Also, it is contemplated that the orifice *45* in the reinforcing flange *30* will be of a diameter slightly less than the diameter of the overflow pipe *22* so that it may be slid into position upon the pipe with a tight, resilient fit.

This valve guide may also be made of a synthetic resin, such as a high-impact styrene which, though comparatively rigid, is sufficiently resilient to yield to shock or pressure and will not easily break. This will require a modified construction of an arm *44a* to provide a connection to an overflow pipe *22*, such as illustrated at FIG. 5. A slot *47* is cut into the end of the arm *44a* to the orifice *45a*. A wing nut *48* extends through suitable holes in the end of the arm *44a* transversely of the slot, and this wing nut *48* is adapted to be tightened to narrow the slot and decrease the diameter of the orifice *45a*. Accordingly, when the arm *44a* is mounted upon the overflow pipe *22*, it is secured in position with a tight, positive fit by the simple operation of tightening the wing nut *48*.

The valve guide *40* must be positioned on the overflow pipe *22* so that it is directly above the discharge pipe *15*, and in an alignment such that the axis of the guide *40* will be as close as is practical to the vertical axis of the discharge pipe *15*. Actually, a precise alignment of the guide *40* with the discharge pipe *15* is not essential because of the very loose fit of the valve *25* when it is within the guide cup *40*. This permissible leeway in the alignment of the guide *40* with respect to the discharge pipe *15* is advantageous in that it not only permits installation of the valve guide without the need of a precise setting operation, but also permits a standard valve guide structure to be produced which will fit any one of a number of different commercial makes of outlet structures where the location of the overflow pipe *22* with respect to the outlet pipe *15* may vary as much as one-fourth inch.

Also, the valve guide *40* must be placed on the overflow pipe *22* at a selected distance above the discharge pipe. This distance, which may be referred to as the distance of the lower edge *50* of the skirt *41* above the outlet entrance *16*, may be varied somewhat, but on a rule-of-thumb basis, it is preferably one-half the diameter of the outlet pipe *15*. In a conventional water tank which is provided with a two-inch pipe *15*, this distance would be thus one inch.

This positioning of the valve guide above the seat may be varied somewhat from the one-half diameter rule, but it still must be between limits which can be easily established by simple tests. If the guide is too close to the

outlet, the float valve will drop back onto and close the outlet whenever it is lifted into the cup-like guide, for the rush of water past the skirt edge 50 and into the outlet will not provide sufficient buoyancy to support the valve 25. Based upon theoretical considerations, a limiting position would be a distance where the distance of the skirt edge 50 above the outlet entrance 16 is approximately one-fourth of diameter of the pipe 15, or one-half inch.

If the guide is too far above the outlet, the float valve may shift or be thrown laterally and out of alignment with the seat as it drops towards the outlet entrance when the tank is being emptied. This is because of an erratic swirling action of water which occurs as the water closet tank is being emptied and when the water level may actually be below the skirt edge 50. However, this lateral shifting of the valve cannot occur until the outer edge of the shoulder 28 drops below the skirt 41 of the guide. Accordingly, if the lower end of the valve 25 is sufficiently close to the outlet entrance 16 as to be within the influence of water flowing into that entrance before the shoulder of the valve drops below the lower skirt edge 50, lateral displacement cannot occur. A maximum height of the skirt edge 50 above the entrance 16 is approximately one diameter of the pipe 15, or two inches, but as a practical matter, this maximum height may be established as being approximately three-fourths of the diameter of pipe 15, where the bottom of the float valve is substantially within the outlet entrance 16 before the shoulder drops below the lower skirt edge 50.

A further advantage of the valve guide resides in permitting a free seating action as the float valve closes when the water closet is drained. The lift rod 31 upstanding from the float valve 25 is laterally restrained only by the comparatively large orifice 43 and the top 42 of the guide. This permits the float valve 25 to rotate slightly as it rests upon the seat 16. In this manner, the float valve can find a proper seating position every time it closes, and it will also seat at different positions upon each closure to enhance and extend its useful life, variations of closure being illustrated at FIG. 7.

I have now described my invention in considerable detail; however, it is obvious that others skilled in the art can build and devise alternate and equivalent constructions which are nevertheless within the spirit and scope of my invention. Hence, I desire that my protection be limited not by the constructions illustrated and described, but only by the proper scope of the appended claims.

What is claimed is:

1. The combination with a water closet tank having an

outlet entrance seat at the floor thereof, a standpipe adjacent thereto, a float valve adapted to normally rest upon the seat to close the outlet formed as a hollow, generally-hemispherical body with a boss at its top from whence a lift rod upstands, and means to pull the lift rod to lift the valve from the orifice seat, of: a guide, in the general form of an inverted cup, adapted to be mounted within the tank and upon the standpipe a short distance above the float valve, said guide having generally cylindrical walls with a diameter sufficiently large to receive the float valve with a loose fit when it is lifted from the outlet seat, a generally flattened top with an orifice therein adapted to receive the boss of the float valve when the float valve moves into the guide, and means associated with the standpipe to hold the guide above the outlet, whereby when the float valve is lifted, as to drain the water closet tank, it will move upwardly and into the guide with the boss moving into the top orifice and, as the tank is drained, the float valve will be restrained by the guide to drop onto the outlet entrance with the lift rod then being within the top orifice to fit therein with a very loose, sloppy fit, permitting random movements of the float valve as it drops onto the seat without restriction by the movements of the lift rod in the orifice.

2. In the organization set forth in claim 1, where the lower edge of the guide is above the outlet entrance a distance which is approximately one-half the outlet diameter.

3. In the organization set forth in claim 1 where the lower edge of the guide is above the outlet entrance a distance which is greater than one-fourth the outlet diameter and less than one outlet diameter.
